UNITED STATES PATENT OFFICE.

KENNETH HOWIE, OF NORRISTOWN, PENNSYLVANIA, ASSIGNOR TO WILDMAN MFG. CO., OF NORRISTOWN, PENNSYLVANIA, A CORPORATION OF PENNSYLVANIA.

TRICK WHEEL FOR KNITTING MACHINES.

Application filed May 21, 1927. Serial No. 193,280.

The invention concerns a trick wheel or tuck wheel for knitting machines. One object is to provide a construction whereby fine gauges of fabric may be produced, the trick wheel being applicable to a machine of say, for instance, twenty-eight cut.

Another object of the invention is to enable the pattern to be changed as may be desired.

10 A further object is to provide a simple and economical construction.

In the accompanying drawings:

Figure 1 is an edge view of a trick wheel embodying my invention, the wheel being shown at the inclination it would occupy in the machine, this however being arbitrary.

Fig. 2 is a sectional view.

Fig. 3 is a plan view of the body of the wheel, showing the cuts to receive the projections or inserts.

Fig. 4 is a bottom plan view of the cap plate.

Fig. 5 shows various views of one of the insert piece or projections.

25 Fig. 6 shows in perspective one of the plain inserts.

Fig. 7 is a perspective view of one of the shouldered inserts which elevates the needles.

30 In carrying out the invention with the object of providing a trick wheel for the finer gauges of machines, I employ inserts 1, 2 of thin sheet metal which are mounted in the cuts 8 of the body 9 of the wheel.

35 As shown in Fig. 6 some of these inserts 1 are simply plain sheet metal pieces, and as shown in Fig. 7, there are metal pieces or inserts 2 provided with turned over portions 3 which provide the shoulders to engage the butts of the needles.

40 These insert pieces have each a point 4 to bear against the periphery of the wheel body and they have each a notch 5 in its upper edge to be engaged by a rib 6 on the cap piece or plate 7, between which and the main body 9 of the wheel the inserts are held, said plate 7 being held in place by screws 11. The body portion 9 of the trick wheel has a hub 10 by which said wheel is mounted on a suitable support. The inserts are placed in the body of the trick wheel at an angle to the upper and lower faces thereof, this angle being such that when the trick wheel is in place and at an angle to a horizontal plane, the spaces or guide grooves between the ad-

jacent plain inserts will be vertical to receive the butts of those needles which are not to be operated by the trick wheel. Those needles which are to be operated by the trick wheel will be engaged by the shoulders or turned over flanges 3 of the insert pieces 2, which will elevate them to be taken by a suitable cam forming a part of the machine.

The inserts are stamped from thin sheet metal and the shoulders 3 are formed by turning over a part of the stamped piece. This shouldered portion lies outside the wheel body and this is true of the outer end portions of all of the insert pieces. The turned over flanges 3 forming the shoulders 76 extend across the space, or groove, from the insert piece which carries it to the side face of the adjacent insert piece so as to form a shoulder to engage the butt of the needle and lift the same.

By reason of the employment of inserts as the walls between the grooves, these walls can be made of thin sheet metal thus enabling the trick wheel to be produced for the finest gauges.

55 It will be observed that the flanges 3 are turned over at such an angle to the body of its insert member that when placed in the body of the wheel at the prescribed inclination, the free edge of said flange will contact with the adjacent insert piece at a short distance below the upper edge thereof so that the shoulder provided by this flange will be at the bottom of a small recess or notch receiving the butt of the needle, and I have marked one of these notches in Fig. 1 at a. This notch is defined by the flange and by the side wall of the adjacent insert piece.

I claim:

1. A trick wheel for knitting machines having insert pieces mounted therein and spaced apart from each other, some of said insert pieces having flanges extending across the spaces between the said pieces to provide shoulders for engaging the needle butts, others of said insert pieces having no flanges to leave adjoining spaces free to receive the needle butts, substantially as described.

2. A trick wheel for knitting machines having insert pieces spaced apart, some of which have integral flanges turned over from their upper edges to extend across the adjacent space to provide a shoulder for operating the needle and other of said insert 110

pieces having free spaces between them to receive the needle butts idly, substantially as described.

3. A trick wheel for knitting machines having insert pieces with flanges on some of them at such an angle thereto that notches will be formed for the needle butts between adjacent inserts, said flanges forming the bottom of said notches, those inserts which have no flanges providing free spaces for receiving the needle butts idly, substantially as described.

4. A trick wheel for knitting machines comprising a body having cuts or kerfs therein, sheet metal pieces inserted in said cuts and projecting therefrom and means for obstructing the spaces between certain of said insert pieces while the spaces between

certain other insert pieces are left free, said means being carried by certain of said insert pieces, substantially as described.

5. A trick wheel having thin sheet metal pieces inserted therein at an inclination to the upper and lower faces of the wheel, some of said insert pieces having integral flanges turned to lie across the space between adjacent pieces and with the free edges of said flanges below the upper edges of the adjacent insert piece to provide a notch to receive the needle butt of which notch said flange forms the bottom, others of said insert pieces having free spaces between them to receive needle butts idly, substantially as described.

In testimony whereof, I affix my signature.
KENNETH HOWIE.
